(57) **CLAIM**

I claim the ornamental design for downspout elbow tool, as shown and described.

DESCRIPTION

FIG. 1 is a top front perspective view of my new design for a downspout elbow tool.

FIG. 2 is a front plan view of my new design for a downspout elbow tool.

FIG. 3 is a back plan view of my new design for a downspout elbow tool.

FIG. 4 is a top plan view of my new design for a downspout elbow tool.

FIG. 5 is a left side view of my new design for a downspout elbow tool.

FIG. 6 is a right side view of my new design for a downspout elbow tool; and,

FIG. 7 is a bottom plan view of my new design for a downspout elbow tool.

1 Claim, 3 Drawing Sheets
